INVENTOR

Marie Niblo

Miss Fannie Lawrence,

ATTORNEY

UNITED STATES PATENT OFFICE.

MARIE NIBLO, OF SEATTLE, WASHINGTON.

DRAIN AND STRAINER.

1,292,856.

Specification of Letters Patent. Patented Jan. 23, 1919.

Application filed September 21, 1918. Serial No. 355,065.

To all whom it may concern:

Be it known that I, MARIE NIBLO, a citizen of the United States, residing at Seattle, in the county of King and State of Washington, have invented certain new and useful Improvements in Drains and Strainers; and I do hereby declare the following to be a full, clear, and exact description of the invention, such as will enable others skilled in the art to which it appertains to make and use the same.

This invention has reference to a strainer for sinks.

In carrying out the invention it is my purpose to produce a device of this character adapted to be arranged over the drain pipe of a sink or other washing receptacle wherein the liquid will be permitted to drain from the receptacle through the drain or outlet pipe without permitting the passage of solid matter therethrough.

It is a further object of the invention to produce a strainer of a comparatively simple construction, which may be readily arranged in a sink over the drain or outlet pipe therefor, including essentially a reticulated hinge plate having an annular upstanding projector, in the nature of a fence to prevent solid matters passing onto the reticulated plate, the said plate being provided with a valve whereby the reticulations thereof may be covered or uncovered, and the hinge connection of the member permitting of the free drainage of all of the water from the sink through the outlet pipe.

I accomplish the foregoing objects and others by a simple construction, combination and operative arrangement of parts, a satisfactory exemplification of which is illustrated in the drawings.

In the drawings:

Figure 1 is a plan view of the improvement in its entirety.

Fig. 2 is a cross-sectional view.

45 The device comprises a disk 3 adapted to be placed directly over the outlet of a sink and screwed to the latter by screws 17. This disk may comprise inner and outer ring portions 4 and 5 counter sunk to form a seat. The ring is shown as in one piece.

On the outer ring part 5 is secured one leaf of a hinge 6, the other leaf being secured to a flat disk-plate 7 that is of a size to be snugly received in the countersink of the disk 5 and to rest on the seat 4. The

plate 7, is provided with slots or perforations 8, preferably arranged in groups. On the plate 7, outward of the perforations, are upstanding, spaced guard bars 9. The guard bars are in the nature of a grating or fence and are designed to prevent solid matters passing therebetween and onto the perforated plate 7. The plate 7 is centrally provided with an opening receiving a pivot 10, the upper end of the pivot being provided with a handle 11, and the said pivot being engaged by shoulder 14 to a flat perforated valve 12. The valve is designed to turn and normally close the perforated portion of the plate 7. The contracting forces of the plate and valve are such that fluid may not pass therebetween. A nut 13 or other suitable means is provided on the pivot 10 under the plate 7 for regulating the frictional engagement between the valve and the said plate, so, that the valve will prevent the passage of fluid from the sink except through the perforation of the plate 7, when turned open.

The guard or fence, as previously stated, prevents the passage of solid matter onto the perforated plate 7, so that such matters may be collected after the water has been drained from the sink. Should a free passage of water through the sink into the pipe be desired the handle 11 may be employed for lifting open both the valve and plate 7 on the hinge 6, as will, it is thought, be readily understood.

It is believed, from the foregoing description that the simplicity of the construction and the advantages thereof will be apparent, to those skilled in the art to which such invention appertains.

The plate 7, is provided with a slot 16— and the valve 12 with a lug 15— which protrudes down into the slot and limits the travel of the valve on the plate so that when in position in Fig. 1— the perforations in 7 and 12 both register and permit the water to flow out, but when the valve 12 is turned so that the lug 15 is at the other end of slot 16— the holes in plate 7 will be covered by the solid position of the valve 12.

Having thus described the invention, what is claimed as new, is:

1. A strainer of the class described, including a hinged plate having a series of perforations or openings, a guard in the nature of a fence on the plate outward of

said openings, a valve centrally pivoted to the plate designed to cover or disclose the perforations or openings therein, and means for regulating the pressure between the valve and plate.

2. A strainer of the class described including a stepped ring, an annular flat plate in the ring and hingedly connected thereto, said plate having a series of openings or perforations, a fence on said plate surrounding said openings or perforations, a flat valve on the plate pivotally secured thereto and adapted, when actuated, to cover or disclose the openings or perforations in the plate, and means for regulating the con-

tacting engagement of the valve with the plate.

3. A strainer of the class described including a stepped ring, an annular flat plate in the ring and hingedly connected thereto, 20 said plate having a series of openings or perforations, a fence on said plate surrounding said openings or perforations, a flat valve on the plate pivotally secured thereto and adapted, when actuated, to cover or disclose the openings or perforations in the plate.

In testimony whereof I affix my signature.

MARIE NIBLO.
